UNITED STATES PATENT OFFICE.

PAUL ARBON, OF TULSA, OKLAHOMA.

SWIVEL SOCKET.

Application filed August 21, 1923. Serial No. 658,590.

To all whom it may concern:

Be it known that PAUL ARBON, a subject of the King of Great Britain, residing at Tulsa, in the county of Tulsa and State of Oklahoma, has invented certain new and useful Improvements in Swivel Sockets, of which the following is a specification.

This invention relates to an improved form of swivel socket, such as is utilized in the drilling of oil wells, and relates particularly to improvements in the well-known Burns' socket.

Heretofore attempts have been made, as for instance by Miller and Holliday, to construct sockets of the type in question in such a way as to permit the insertion or the removal of the swivel from the socket without disconnecting the cable. In these constructions it has been found that the body and neck of the socket has been weakened to such an extent as to make same impractical for the five and a half inch tools, as in order to place a swivel with a neck on the inside of such a socket so much of the body and the neck has to be cut away as to leave a mere shell to carry the tools.

The main object of the present invention is to so alter the construction of the Burns' socket, heretofore mentioned, as to permit the removal of the swivel and rope without decreasing the strength of the same so that the convenience of this construction may be present in connection with all sizes of tools.

More specifically the present invention includes such features as the removal of the rod to one side of the slot and the provision of a steel bushing, which is inserted at the top of the socket, and capable of adjustment to prevent the line from coming out.

Reference will be had to the accompanying drawing forming a part of this specification and wherein like numerals of reference designate corresponding parts throughout the several views, in which—

Fig. 1 is a side elevation showing the parts assembled,

Fig. 2 is a vertical sectional view,

Fig. 3 is a transverse section on line 3—3 of Fig. 1,

Fig. 4 is a transverse section on line 4—4 of Fig. 1, and

Fig. 5 is a similar view on line 5—5.

Referring now to the details of construction, reference character A designates the body of a socket which is provided at its lower end with the usual threaded opening a for

receiving the upper extremity of the tools supported by the socket. The body A is formed with the cylindrical cavity B which forms an upward extension of the threaded opening a. The upper end of the socket member is formed with a longitudinal bore C which communicates at its lower end with the cylindrical cavity B and the threaded opening a. The cylindrical cavity B and the longitudinal bore C are concentric with the longitudinal axis of the body and due to the size of the bore C an annular shoulder or abutment c is formed which engages the swivel slip. As is common in this type of socket the cylindrical cavity B merges on one side into the lateral opening D, the upper end of which terminates below the plane of the abutment c and the lower end of which terminates at a point approximately midway the length of the socket or slightly therebelow so as to form an opening of sufficient size as to permit the insertion of the swivel slip.

The upper end of the longitudinal bore C is abruptly enlarged to form a shoulder and recess for the reception of the steel bushing E, the latter terminating flush with the upper end of the socket body and having its central opening flush with the bore C. This steel bushing E is formed with a lateral opening e which corresponds with the lateral slot c' formed in the neck of the bushing and which slot extends from the lateral passage D through the upper end of the body. Of vital importance in this connection is the location of this slot c' which, as shown in Figs. 3 and 4, is located with its central axis to one side of the longitudinal bore C so that the walls c'' merge directly into the adjacent wall of the bore. To accommodate for this arrangement the lateral opening e is similarly arranged so as to permit registration with the slot c' when desired. A series of set screws F are arranged to project through the neck of the socket body to engage the steel bushing E to prevent the movement of the latter.

For closing the lateral passage D to prevent the escape of the swivel I have arranged the rod G, the lower end of which is shaped to form a tapered shank which seats in a correspondingly shaped socket g' formed in the lower wall of the passage D. From the socket g' this rod G extends upwardly through an opening g, the latter being aligned with the socket g', and extending from the upper wall of the passage

D vertically through the shoulder of the socket. Obviously the pin G is arranged to one side of the slot c' but is sufficiently adjacent the center of the passage D to retain a swivel therein. In Figure 1 a lateral opening g'' is shown to permit the insertion of a suitable tool to engage the lower end of the rod G to assist in the removal of the latter.

10 The body of the pin G is of sufficiently resilient material to permit its removal which is accomplished by first inserting a tool in the lateral opening g'' to release the shank from the socket and then elevating same above such socket so as to allow the body of the rod to be bent until the shank is beyond the lower wall of the opening D, at which point the entire member can be lowered and the upper end will 20 be withdrawn from the opening g. To replace or insert a new rod the operation is the reverse in that the upper end of the rod is inserted in the lower end of the opening g and then moved upwardly. Obviously this 25 member is bent until the shank end passes the lower wall of the lateral opening D at which point this lower end returns to its normal position and can be lowered into the socket g'. The surface of the socket adjacent the upper end of the opening g is 30 flattened to facilitate the necessary drilling operation, this, however, is common in the art and does not form an element of the present invention.

35 In use, the swivel shown in Fig. 2 in dotted lines, can be removed or replaced by the removal of the pin G and the movement of the steel bushing E, the latter being caused to register with the opening c'. By 40 these adjustments it will be obvious that the swivel and cable can be moved as a unit. Also it will be observed that I have pro-

vided a construction which, while it has all of the desired features of the Miller and Holliday socket, has not the disadvantage of being weakened to any degree. The present socket is capable of use with any type or size tool.

Having thus described my invention what I claim as new and desire to secure by Letters Patent is:—

1. A swivel socket formed at its lower end to connect with well tools, a swivel chamber and a bore of smaller diameter extending from said swivel chamber through the longitudinal axis of the socket body, a transverse slot extending from the bore and communicating therewith and being offset with relation to the longitudinal axis, a split bushing arranged within said bore and adapted 60 for movement to close the transverse passage, and a pin for closing communication to the chamber.

2. A swivel socket body formed with a threaded lower end and a central chamber, 65 a transverse passage communicating with said chamber through the neck of said body, said body being formed with a transverse slot communicating with said bore, a steel bushing formed with a slotted side wall 70 adapted for registration with the transverse passage and means for locking said bushing in adjusted position.

3. The substance of claim 2, characterized in that a vertical pin is provided at one side 75 of the transverse slot for closing the lateral passage communicating with the chamber.

4. The substance of claim 2 characterized in that the steel bushing is seated flush with the surface of the bore and is adapted for 80 rotary adjustment, and fastening means for locking the collar in adjusted position.

In testimony whereof I affix my signature.
PAUL ARBON.
